UNITED STATES PATENT OFFICE.

CLARENCE I. B. HENNING, OF WILMINGTON, DELAWARE, ASSIGNEE TO E. I. DU PONT DE NEMOURS & COMPANY, OF WILMINGTON, DELAWARE, A CORPORATION OF DELAWARE.

PRIMING MIXTURE FOR PROPELLANT EXPLOSIVES.

No Drawing.

Application filed November 17, 1920. Serial No. 424,692.

To all whom it may concern:

Be it known that I, CLARENCE I. B. HENNING, a citizen of the United States, and a resident of Wilmington, in the county of New Castle, and State of Delaware, have invented a certain new and useful Priming Mixture for Propellant Explosives, of which the following is a specification.

This invention relates to priming or igniting mixtures for propellant explosives, and comprises a priming charge containing as an essential constituent hexanitrodiphenylamine.

I have found that hexanitrodiphenylamine has properties which make it specially valuable as a constituent of primers for modern progressive-burning smokeless powders, the other ingredients of the priming mixture comprising, for example, potassium chlorate and antimony sulphide.

Compositions made according to my invention may be illustrated by the following examples:

	Parts by weight.		
	I.	II.	III.
Potassium chlorate.....	50	50	35
Lead sulpho-cyanide.....	25	23	35
Mercury fulminate.....	20	17	35
Antimony sulphide.....	5	10	5 to 10
Hexanitrodiphenylamine.....			

These igniting mixtures, which are intended for use in small arms ammunition,

are characterized by containing hexanitrodiphenylamine, by becoming ignited by not detonating when struck lightly, and by being adapted to ignite a propellant explosive.

It will of course be understood that my invention is not limited to the exact proportions given in the above examples, or to the particular combination of substances, other than hexanitrodiphenylamine, therein mentioned.

I claim:

1. An igniting mixture for small arms ammunition containing hexanitrodiphenylamine, said mixture becoming ignited but not detonating when struck lightly, and being adapted to ignite a propellant explosive.

2. A priming mixture comprising potassium chlorate, antimony sulphide, and hexanitrodiphenylamine.

3. A priming mixture comprising potassium chlorate, antimony sulphide, and from about 5 to 10% of hexanitrodiphenylamine.

4. A priming mixture comprising potassium chlorate, antimony sulphide, lead sulpho-cyanide, and hexanitrodiphenylamine.

5. A priming mixture comprising 50 parts of potassium chlorate, from about 20 to 17 parts of antimony sulphide, from about 25 to 23 parts of lead sulpho-cyanide, and from about 5 to 10 parts of hexanitrodiphenylamine.

In testimony whereof I affix my signature.

CLARENCE I. B. HENNING.
